UNITED STATES PATENT OFFICE.

WILLIAM H. ARNOLD, OF OAKLAND, CALIFORNIA.

COMBINATION CAN-OPENER.

1,250,413.

Specification of Letters Patent.

Patented Dec. 18, 1917.

Application filed June 2, 1916. Serial No. 101,334.

To all whom it may concern:

Be it known that I, WILLIAM H. ARNOLD, a citizen of the United States, residing at Oakland, in the county of Alameda, State of California, have invented certain new and useful Improvements in Combination Can-Openers; and I do declare the following to be a full, clear, and exact description of the invention, reference being had to the accompanying drawings, and to the characters of reference marked thereon, which form a part of this application.

This invention relates to improvements in household appliances and particularly to a device used for the purpose of opening cans of all kinds, the object of the present invention being to produce a can opener which can be used both for opening that form of sealed cans which must be cut open and also those kinds which have a projecting lip which the can opener engages and rolls a portion of the can to rip it open. My improved invention is intended to apply to all sizes of cans and to be capable of use and re-use on both the types of cans indicated above, this present application being intended to cover certain improvements over that structure shown in my Patent Number 1,095,369, dated May 5th, 1914.

A further object of the invention is to produce a simple and inexpensive device and yet one which will be exceedingly effective for the purposes for which it is designed.

These objects I accomplish by means of such structure and relative arrangement of the parts as will fully appear by a perusal of the following specification and claims.

In the drawings similar characters of reference indicate corresponding parts in the several views.

Figure 1 is a side elevation of the opener showing a guard covering one end of the same.

Fig. 2 is a similar view showing the guard covering the opposite end.

Fig. 3 is a bottom plan view showing the guard disposed at right angles thereto.

Fig. 4 is a fragmentary view in perspective of the opening jaws used on the type of can having projecting lips for rolling the cover of the can to rip it open.

Fig. 5 is a detached view of the adjustable cutter.

Fig. 6 is a sectional view taken on a line Y—Y of Fig. 2.

Fig. 7 is a sectional view taken on a line X—X of Fig. 2.

Referring now more particularly to the characters of reference on the drawings, I first provide a substantially flat body member 1. At one end of this body member 1 are formed a pair of jaws 2 which are substantially semi-circular in cross section and are disposed in opposed relation with respect to each other. These jaws 2 are spaced apart to form an intermediate slot 2^b. The jaws 2 taper toward their outer ends.

These jaws 2 are for use in opening cans which have the projecting lip and are adapted to be rolled around the opener to allow the cover to be ripped open. The lip is received into the slot 2^b and the jaws are then turned so that the lip and the cover will roll around such jaws. The jaws being semi-circular in cross section allow the lip and cover to roll into and lock into the same so as to form a firm grip. After the cover has been ripped open the tapered structure of the jaws allows the opener to be readily removed from the tin.

The opposite end of the member 1 has its edges turned downwardly, as at 3 and 4, to form a substantial channel in the underside thereof. The top of this channel is cut out into a slot, as at 5, movable in which slot 85 is an adjustable cutter 6. This cutter 6 is formed as a component part of a plate 7 slidable within the channel and having a rib 8 extending through the slot 5 and terminating in a finger plate 9 on the upper side of 90 the member 1. This end of the member 1 terminates in a pointed spear 10. The side 3, as at 3^a, extends farther along the member 1 than does the side 4, and the side 4 terminates in a sloping end 4^a, all for a purpose as will presently appear.

The member 1 is provided with a substantially central slot 11 slidable in which is a pin 12 turnable on which pin 12 is the inclosing guard 13, such guard flaring outwardly from the pin 12 to form a substantially curved handle member for the device which may be extended from one end to the other in order to guard the ends and be used as a handle member for operating the appliance as will be apparent.

The guard 13 has an inturned lug 15 which snaps between the members 2 when the guard is turned to that end of the appliance which holds the said guard rigid 110

with respect to the appliance. This would be the position shown in Fig. 1. When in this position the spear 10 may be inserted in the center of the can and the finger member 9 can then be pressed to slide the cutter 6 to any desired position in order to conform to the relative size of the can and thereupon the cutter may be used to cut out a section of the can in the usual manner.

- 10 One end of the slot 11 terminates at a point slightly past the end 3^a of the side 3 and the opposite end curves slightly, as at 11^a, toward the said side 3^a. When the guard 13 is to be used over the spear 10, 15 it is turned completely around from the position shown in Fig. 1, and the pin 12 is drawn through the slot 11 and forced upwardly into the curved end 11^a. This action brings one side of the end of the guard 20 13 into clamping engagement with the end 3^a and the spear 10 is then snapped past the lug 15 and this holds the guard 13 rigid to be used as a handle with no chance of the same slipping off of the spear 10 which 25 might result in giving the hand of the operator a severe cut. This is the position shown in Fig. 2.

When in this position the appliance would then be used for opening cans which have 30 projecting lips arranged for engagement between the jaws 2 whereby the portion of the can may be rolled around the jaws 2 to open the can. When the can is opened, the tapered position of the jaws 2, aided by 35 their spaced relation and their semi-circular shape, allows the appliance to be readily withdrawn from the roll of tin which has been made with the opening of the can. Then when the guard 13 is to be again 40 moved around to cover the jaws 2, it is necessary to first disconnect the lug 15 from the spear 10, slip the pin 12 out of the curved end 11^a and project it horizontally

down through the slot 11. This brings its pivotal point to that position which relieves 45 it of any binding effect against the side 3^a whereupon it can be turned to right angles as shown in Fig. 3 and then complete movement again made to close the jaws 2 as shown in Fig. 1. The sloping side 4^a allows 50 of the free movement of the guard 13.

The ends of the jaws 2 are curved to form a guiding recess 2^a, which guides the projection on the can into the space between said jaws. 55

The lug 15 combined with a pair of teats 16 cut in either or each side of the guard 13 can be used for removing bottle caps.

From the foregoing description it will readily be seen that I have produced such 60 a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim. 65

Having thus described my invention what 70 I claim as new and useful and desire to secure by Letters Patent is:

A guard mechanism for tools comprising the combination with a flat tool shank, an upturned side on the edge of the shank, 75 such shank being provided with a slot terminating at one end at a point beyond the end of the upturned side and turning at the other end toward said side, a guard handle provided with a pin movable in said slot 80 and arranged to be moved into the curved end thereof to bring the edge of the handle into clamping engagement with the upturned side. 85

In testimony whereof I affix my signature. 85
WILLIAM H. ARNOLD.
